PACKAGE OPENER

William P. Martin, Stickney, Ill., assignor of one-fourth to Joseph Lustfield, Cicero, Ill.

Application June 2, 1933, Serial No. 673,995

1 Claim. (Cl. 131—59)

My invention relates or pertains to various advantageous features of novelty and betterment in appliances for opening or slitting packages or containers whereby access to their contents may be readily had.

More specifically, the invention concerns improved means for cutting or slitting the packages or wrappers of cigarettes to render their contents easily available.

10 An aim of the invention is to provide a construction of this character which merely cuts the container without removing any portion thereof and in such a manner as to leave a tab to cover the opening through which the cigarettes may be extracted in the usual facile manner.

20 A further purpose of the invention is to supply improved means of this type which will not cut or injure the cigarettes while the package housing them is being operated upon.

25 An added feature of the invention is the production of an apparatus of this general character which is operated by a spring-motor so that the act of placing the package in position releases a catch, thus allowing the motor to revolve a cutting blade to perform the slitting operation.

Still an additional salient feature of the new device is the elimination of all danger or injury to the user of the appliance.

30 To enable those acquainted with this art to understand the invention fully both from structural and functional standpoints, in the accompanying drawing a present, preferred embodiment of the invention has been illustrated 35 in detail, and, for simplicity, like reference numerals have been employed throughout the several views to designate the same parts.

In the drawings.

40 Figure 1 is a vertical section through the appliance with a part shown in elevation and with the cigarette package in position for being slit;

Figure 2 is a horizontal section through the structure with no cigarette package in position;

45 Figure 3 shows the slit or cut in the package, a portion only of the latter being depicted; and

Figures 4 and 5 illustrate the spring-motor mechanism in side elevation and in plan, respectively.

50 Referring to the drawing, it will be seen that the device includes a casing 11 containing any suitable form or type of spring-motor adapted to be actuated or released by a catch 12, which when pushed releases the spring-motor mechanism to cause a one-half revolution of an up-

right shaft 13 which is operatively connected to the motor.

As is customary with spring-motors of this general form, the spring of the motor referred to may be wound up by turning the handle 14 which may be detachable or demountable, if desired.

5 Motors of this character, such as are shown in Patents Nos. 621,185 and 666,074, with slight modification, may be satisfactorily employed in the present mechanism.

10 Referring more specifically to such a suitable spring-motor mechanism which may be satisfactorily employed, attention is directed to the illustrations of Figures 4 and 5.

15 The upstanding catch or release finger 12 is carried on or secured to a horizontal arm 112 rockingly mounted on a fixed shaft 113, such arm being normally yieldingly held against a stationary stop 116 by means of a coiled spring 114 encircling shaft 113 and having one end bearing against a stationary abutment 115 and its opposite end pressing against the arm.

20 Thus spring 114 holds arm 112 in such position that the projection or erect finger 12 is in its unoperated position as presented in Figure 2.

25 A hook 117 is fulcrumed at 118 on a lateral extension of arm 112 and such hook is biased to rock counterclockwise, as viewed in Figure 5, by a bow-spring 119 fastened at one end to the 30 fulcrum-pin 118 and at its other end at 120 to the hook, the tail of the latter being equipped with an antifriction roller 121.

35 Another lower rock-arm 122 is mounted for oscillation on shaft 113 and is equipped with a coiled spring 124 pressing at one end against the projection 115 and at its opposite end against the arm tending to turn the latter counterclockwise as viewed in Figure 5, the arm normally resting against a fixed stop 125.

40 At its free end such arm 122 carries an upstanding lug or projection 123 adapted by its movements to release shaft 13 to, and to lock it against, rotation.

45 The power-spring, not shown, is encased in a housing or shell 126 and the central spring-actuated shaft 131 thereof has a large gear 127 meshing with a small gear 128 on the lower enlarged end of shaft 13 so that the unwinding of the spring, when it is permitted to expand, performs the shaft rotation function.

50 Such lower end portion of shaft 13 has a cam 129 with a pair of downwardly projecting lugs 130, 130 180° apart with which the member 123 is designed to co-act to hold shaft 13 from turning, 55

except when released by the inward movement of finger 12.

When finger 12 is forced inwardly, it rocks arm 112 correspondingly against the action of its spring and such movement of the arm carries the hook 117 with it.

In view of the fact that the hook overlaps and engages a portion of the outer surface of arm 122, the latter also is rocked in like manner, causing lug 123 to release projection 130, whereupon cam 128 and shaft 13 begin to rotate under the action of the power-spring functioning through the intermediate intermeshing gears 127 and 128.

As soon as cam 129 begins its rotation, it engages the roller 121 on the tail of the hook and rocks the hook about its axis sufficiently to release it from arm 122, whereupon such arm, under the influence of its spring 124, again swings back against its stop ready to engage the next cam projection 130, whereby for each actuation of the finger 12, shaft 13 will make one-half revolution only, even though the finger 12 remains pressed inwardly.

Upon release of the finger, it and its arm 112 return automatically to their original unoperated positions and the bevelled hook 117 again overlaps and engages the lower arm 122.

As is fully illustrated in the drawing, such erect shaft 13 is revolvable in a bearing 15 in a bearing-block 16 mounted on or integral with an upright inner wall 17 apertured in its lower part to receive the member 12 when the latter is forced inwardly by the package of cigarettes 18, the normal, unoperated position of the part 12 being shown out of such recess or opening in Figure 2.

Casing or housing 11 is mounted on or depends from a main support 19 from which the wall 17 extends upwardly, and such support 19 is apertured at 21 to provide for the sliding movements of the element 12.

The inner end wall 17 joins together two parallel sidewalls 22, 22 spaced apart a distance practically equal to the thickness of the cigarette packages to be slit by the device, the outer vertical edges or margins of such side-walls being recessed in register at 23 for the reception of the fingers and thumb of the operator while he grasps the package and pushes it into the space between the sidewalls.

From the foregoing, it will be apparent that a portion of the top surface of the plate or support 19 forms the floor of a compartment or pocket adapted to receive the package of cigarettes, the side and inner end walls of the compartment being composed of the members 22 and 17.

These upstanding, confining side-walls 22, 22 are slightly taller than the length of the package 18, but their inner portions are reduced in height at 24, 24 to be of the same height as the wall 17 which is slightly less than the height of the package 18.

Shaft 13 above the bearing-member 16 has a round head 25 fixedly held thereon by a pin 29 or otherwise, whereby the head revolves with the shaft, the upper face of the head having two pairs of upstanding studs 26, 26 designed and adapted to fit in correspondingly-spaced holes of two thin, wafer-like, double-edge blades 27, 27 which locate the two blades in proper position with relation to the axis of the shaft.

Above the blades a clamping or holding disc 28 is used which is apertured to conform to the positions or locations of the pins or studs, such disc being firmly and securely held in place by a

knurled nut 29 on the top, screw-threaded end of the shaft.

From what precedes, it will be apparent that the blades are firmly clamped on the head by the structure described.

As is clearly depicted, a substantial operative portion of each sharp-edged blade extends beyond the periphery or margin of both the head and the blade clamping or securing disc, such protruding parts of the blades constituting their active cutting or slitting sections.

It will be observed also that the blades are arranged at an oblique angle to any radius of the head extended through the blade, this arrangement of parts being resorted to in order to procure the especial or particular shearing and cutting action hereinafter referred to.

It may be noted in addition that the blades may be reversed end for end and also edge for edge, whereby by such adjustment or modification of position each blade may be made to have four active cutting parts, whereby when one section becomes dull a new one may be used to replace it.

The appliance operates practically as follows:

When the package 18 of cigarettes is inserted or introduced between the companion side-walls 22, 22 and is pushed inwardly fully home, the container, which is ordinarily made of paper, possibly covered with a wrapper of cellophane, necessarily engages the release-bar 12 and pushes it along ahead of it into the cavity in the wall 17.

By the time the package of cigarettes has been fully introduced into such pocket or compartment, the member 12 will have released the spring-motor which rapidly revolves the shaft and its outstanding blades in the direction indicated by the arrow for a half revolution.

During the first portion of such rotation, the mechanism, including the blades, is accelerating and acquiring the needed momentum.

Thereafter, the active blade first engages the corner of the package just slightly beneath its top wall at the corner 31 of the pocket and shears and slices across such corner due to the peculiar angular position of the blade on its supporting, revolving head.

It is important that the relatively-flimsy paper of the package shall not cave in under such corner slitting action, and this is successfully accomplished due to the fact that such corner of the package is held in position by the cumulative supporting and bracing action of the corresponding top and wide and narrow side-walls of the package, supplemented by the fact that in cutting the corner the blade advances and at the same time is drawn more or less lengthwise across the corner.

Such initial glancing or oblique corner cut having been successfully negotiated without crumpling the paper and without cutting or injuring the cigarettes, the blade, as will be readily understood, being introduced between the top ends of the cigarettes and the under-surface of the top wall of the package or container, the blade advances through the package and slits a part of the wider side-wall and the full width of the narrow side-wall which bears against the abutment wall 17.

During all, or a material part, of such cutting action, the blade, while performing the cutting function, is simultaneously drawn lengthwise to effect what may perhaps be termed a slicing action.

The final cut of a portion of the other wide side-wall is brought about more like the action of a pair of shears, the blade functioning as one element of the shears and the top surface of the 5 part 24 of the corresponding stationary wall acting as the companion or correlated element of the shears.

The complete cut 32 (Figure 3) having been made, the blade automatically stops in the position of the lower blade in Figure 2 and the slit 10 package is removed by hand from the compartment defined by the walls 17, 22.

By temporarily turning back the paper tab 33 just above the cut 32, one or more cigarettes may 15 be abstracted from the package in the usual manner, and after these have been taken out the remainder can be readily withdrawn as desired.

The outstanding characteristic of this mechanism is the peculiar manner in which the blade 20 does its work, because experience has shown that the desired result can be satisfactorily accomplished by this mechanism, whereas experimental appliances working on somewhat different principles have demonstrated themselves to be 25 failures.

The cutting mechanism of the device is usually covered or housed in a shield 34 which over-lies the path of travel of the knives, so that there 30 is practically no danger of anyone being injured or cut by the apparatus, and in ordinary service the fingers of the operator do not approach the knives.

Those acquainted with this art will readily understand that the invention defined by the 35 appended claim is not limited and restricted to the precise and exact details of construction, and that modifications may be made therein without departure from the heart and essence of the inven-

tion and without the loss or sacrifice of any of its material benefits and advantages.

I claim:

In a cigarette package opener, the combination of a floor, an end and two side walls upstanding from said floor and unitedly forming a compartment with an open end adapted to receive and snugly accommodate a package of cigarettes advanced into said compartment by sliding through said open end on said floor, a spring-motor, a 10 shaft rotated a half revolution only by each actuation of said motor, a member in said compartment in the path of insertion of said package and movable by the entering package to release said spring-motor whereby such motor 15 revolves such shaft one-half revolution, a support on said shaft, and two sharp-edged blades mounted on said support and each extending beyond the periphery of said support, each said blade occupying a position on said support oblique to the radius of the shaft through the center of the blade, whereby one of said blades during a half rotation of the shaft first engages and in a slicing manner cuts through the top portion of an upright corner of the stationary package resting on the floor of and confined by the 20 walls of said compartment between the top ends of the cigarettes in the package and the adjacent inner surface of the corresponding top wall of the package and then completes the slit of the walls 30 meeting at said corner and finally slits the wall opposite to one of said first package walls, said final cut being comparable to that of a pair of shears wherein the blade forms one cutting element of the shears and the end of one of said 35 compartment walls constitutes the correlated cutting element of the shears.

WILLIAM P. MARTIN.
